DESK CALENDAR BASE

Leslie L. De Mathe, Seattle, Wash., assignor to De Mathe-Walker, Seattle, Wash., a corporation of Washington

Filed Oct. 28, 1960, Ser. No. 62,662

Term of patent 14 years

(Cl. D74—5)

FIG. 2

FIG. 3

FIG. 4

FIG. 5

FIG. 1

Fig. 1 is a top perspective view of a desk calendar base showing my new design;

Fig. 2 is a front elevational view thereof;

Fig. 3 is a side elevational view;

Fig. 4 is a top plan view; and

Fig. 5 is a rear elevational view thereof.

I claim:

The ornamental design for a desk calendar base, as shown.
